UNITED STATES PATENT OFFICE

2,508,729

AUTOMOBILE WATER CIRCULATING HEATER

Heinrich Stein, Chicago, Ill.

Application May 5, 1948, Serial No. 25,227

4 Claims. (Cl. 257—137)

1

My invention relates to heaters primarily used in connection with vehicles, the said heaters being heated by virtue of the circulating liquid used to cool the engine of an automobile or vehicle of like character.

An important object of my invention is to provide a liquid circulating heater which utilizes the circulating liquid used for cooling the engine of a vehicle, the said heater being so disposed as to radiate heat to the interior of the vehicle simultaneously providing the additional function of acting as an auxiliary cooler for the liquid before it is returned to the radiator of the vehicle for ultimate cooling prior to its re-circulation through the engine.

A further object of my invention is to provide a heater unit of the aforementioned character which consists of a central cylindrical section subdivided into two compartments, an intake compartment and an exhaust compartment, whereby the liquid is transferred from one of the said compartments to the other by means of radially disposed U-shaped communicating tubular means; all of the said tubular means being retained in place by an outer casing and a series of rather thin cylindrical radiating vanes.

A further object of my invention is to provide a circulating liquid type of heater which has the intake positioned coincidently with the central axis of the said heater unit, whereas the exhaust thereof is connected to any point within the radial confines or circular area of the central unit.

A further object of my invention is to provide a circulating liquid-type of heater of the aforementioned character in which the circulation of the liquid taken in to the central part of the heater is dispersed radially outwardly, upwardly, and then inwardly through U-shaped connecting means to complete the cycle of liquid circulation or operation.

A further object of my invention is to provide a heater of the aforementioned character which is practical in construction, useful for the purpose for which it is purported to be used, and of such simple elemental structural assemblage as to warrant economical production thereof in quantity manufacture.

Other objects, ancillary advantages, and novel features embraced in my invention will become readily apparent from an examination of the accompanying drawings, elucidated further in the ensuing description, where like numerals are used to designate like parts, and in which;

Fig. 1 is a view of my invention shown connected underneath the hood of a vehicle shown in phantom lines in the illustration.

2

Fig. 2 is a top elevational view of the heater unit comprising my invention.

Fig. 3 is a cross-sectional view taken substantially on the lines 3—3 of Fig. 2.

5 Fig. 4 is a fragmentary cross-sectional view taken substantially on the lines 4—4 of Fig. 3.

Referring to the various views, my invention is generally designated 5, and it is connected through piping or tubing 6 to the jacket of the 10 engine 11 of a vehicle at the point 8 so as to receive thereinto the heated liquids coming from the engine subsequently to their absorption of the heat generated by the engine in its operation in order to effect cooling of the engine. The said 15 liquid is then transmitted through the heater 5 and through the outlet 7 communicating and being connected at the point 9 to the radiator 10 of the vehicle; the said radiator being used primarily for cooling purposes. Thus the heater 20 5, which I provide, has a dual function, that of heating the interior of a car through the heat currents dissipated thereby, and generally indicated by the arrows designated 27, and a second function of pre-cooling the heated liquids to be 25 ultimately cooled by the engine radiator prior to recirculation.

The general construction of my heater invention is best illustrated in the views illustrated in Figs. 2, 3, and 4, and consists primarily of a central cylindrical section 12 having a side wall 13 with a reduced shoulder portion at 14 in order to seat the partition element 15.

A bottom is integrally formed and a separate top element 12 is seamed at 16 in order to form an enclosure of the said central cylindrical section 12 subdivided into two compartments designated 19 and 20. The compartment 19 is the outlet from the heater for the circulating liquid 28, whereas the bottom compartment 20 is the intake from the jacket of the engine and is fed by the 40 tubing 7, the chamber or compartment 19 being connected to the tubular connection 6 which terminates at 18.

The side walls 13 of the central unit 12 are suitably drilled in order to receive at the top and bottom thereof the U-shaped sections designated 22 so as to form communication with the lower compartment 20 and with the upper compartment 19, to provide continuous circulation through the said U-shaped tubular elements 22.

50 The same are radially positioned as indicated in Fig. 2 at predetermined spacing and held in assemblage by the perimetral cover 21. The said tubular sections are also held in place by a series of tubular elements 26 of rather thin metallic 55 material, which serve a dual function, namely, of

rigidly reinforcing and holding in place the said tubular sections 22, the cylindrical sections 26 being suitably drilled in order to hold in rigid relationship the U-shaped tubular sections 22 heretofore mentioned.

It is to be noted that the intake 7 is bent to form two elbow portions so that its terminal extension 25 will enter into the compartment 20 at the central or axial point of the heater held in the partition element 15 at 17. Thus the water is caused to circulate first from the radiator 10 through the motor 11 and then through the connection 8 and the pipings 7, ultimately passing through the compartment 20 where the hot water is then circulated in the direction of the arrows through the inlets 24 of the tubular elements 22; the outlets 23 of the said tubular elements 22, communicating with the compartment 19, causes the liquid to circulate outwardly from the heater through the tubular connection 6 back to the radiator 10, thus completing the cycle of operation. The hot water brought from the engine jacket is thus caused to circulate through the U-shaped tubes and then brought back to the radiator. In circulating through the U-shaped tubes, heat waves will be transmitted or radiated to the interior confines of the vehicle as indicated by the arrows 27.

The cylindrical vanes 26 are preferably spaced in order to allow air currents to circulate therethrough and become heated. The liquid 22 absorbs the heat from the jacket of the engine, hence cooling the engine, thus the heat is radiated to heat up the interior confines of a vehicle so that the heater thus acts as a preliminary cooler to the liquid which is then circulated through the radiator 10 for final cooling and recirculation through the jacket of the engine 11 for cooling the same.

I am aware that many heaters have been created for the same results as my heater will provide; however, most of the heaters are usually heated through the exhaust gases resulting as a product of combustion of the gases and the explosions translated through the engine to furnish motive power. In my particular instance, I wish to stress that I am utilizing, rather than exhaust gases for heating purposes, the heated liquid which is used as a coolant for the engine of the vehicle.

I believe, I have herein described rather succinctly the nature and construction, as well as the operation of my invention, and inasmuch as the same is susceptible of various modifications and improvements, I hereby reserve the right to all modifications and improvements coming within the scope and spirit of my invention, as well as any that are embraced in the accompanying illustrations and drawings, and elucidated in the foregoing description; my invention to be limited only to the subjoined claims.

Having thus disclosed and revealed my invention, what I claim as new and desire to secure by Letters Patent is:

1. A liquid circulating heater comprising, a central section subdivided into a liquid inlet compartment and a liquid outlet compartment, U-shaped tubular means having its termini connected respectively to the said inlet compartment and the said outlet compartment, liquid inlet means connected to the mid-portion of the said inlet compartment, liquid outlet means connected to the said liquid outlet compartment, the longitudinal axes of the said U-shaped tubular means

being disposed in right angular relationship to the axis of the said central section, and tubular cylindrical vane means provided with bored means for rigidly securing the leg portions of the said U-shaped tubular means and adapted to radiate heated currents therefrom.

2. A liquid circulating heater comprising, a central section subdivided into a liquid inlet compartment and a liquid outlet compartment, U-shaped tubular means having its termini connected respectively to the said inlet compartment and the said outlet compartment, liquid inlet means connected to the mid-portion of the said inlet compartment, liquid outlet means connected to the said liquid outlet compartment, the longitudinal axes of the said U-shaped tubular means being disposed in right angular relationship to the axis of the said central section, the said U-shaped tubular means being disposed in radial formation, and tubular cylindrical vane means provided with bored means for rigidly securing the leg portions of the said U-shaped tubular means and adapted to radiate heated currents therefrom.

3. A liquid circulating heater comprising, a central section subdivided into a liquid inlet compartment and a liquid outlet compartment, U-shaped tubular means having its termini connected respectively to the said inlet compartment and the said outlet compartment, liquid inlet means connected to the mid-portion of the said inlet compartment, liquid outlet means connected to the said liquid outlet compartment, the longitudinal axes of the said U-shaped tubular means being disposed in right angular relationship to the axis of the said central section, perimetral cover means rigidly securing the outer portions of the said U-shaped tubular means, and tubular cylindrical vane means provided with bored means for rigidly securing the leg portions of the said U-shaped tubular means and adapted to radiate heated currents therefrom.

4. A liquid circulating heater comprising, a central section subdivided into a liquid inlet compartment and a liquid outlet compartment, U-shaped tubular means having its termini connected respectively to the said inlet compartment and the said outlet compartment, liquid inlet means connected to the mid-portion of the said inlet compartment, liquid outlet means connected to the said liquid outlet compartment, the longitudinal axes of the said U-shaped tubular means being disposed in right angular relationship to the axis of the said central section, the said U-shaped tubular means being disposed in radial formation, perimetral cover means rigidly securing the outer portions of the said U-shaped tubular means, and tubular cylindrical vane means provided with bored means for rigidly securing the leg portions of the said U-shaped tubular means and adapted to radiate heated currents therefrom.
